UNITED STATES PATENT OFFICE.

AVERY J. HILTON, OF GLOUCESTER, MASSACHUSETTS.

SAXOPHONE.

Application filed December 7, 1925. Serial No. 73,707.

This invention relates to improvements in saxophones.

It is an object of the invention to facilitate in a saxophone the playing of tones of a higher register without requiring the actuation of keys located at a point on the saxophone which the player can reach with difficulty only, or without requiring the actuation of keys which, while located in readily accessible position, cannot easily be operated simultaneously with other keys necessary for the production of certain tones.

Another object of the invention is to provide in a saxophone a single key by means of which several valves of higher register tones may be operated and to arrange the key for actuating these higher tone register valves at a point on the saxophone adjacent those keys which are to be operated when tones of a lower register are to be played.

An additional object of the invention is to provide in a saxophone means for rendering resonant certain tones which cease to be resonant when certain keys on the saxophone are operated, and to effect this resonance automatically upon operation of that key which also controls the valves for producing the tones of higher register.

Additional objects will become apparent from a perusal of the following specification, in which reference is made to the accompanying drawing.

In the drawing:

Figure 1 is a side elevation of a portion of the body of the saxophone;

Figure 2 is a side elevation seen from another side of the same body portion;

Figure 3 is a fragmentary side elevation of a smaller portion of the saxophone, again seen from a different side, to illustrate certain auxiliary valves;

Figure 4 is a sectional view on line 4—4 of Figure 1;

Figures 5 and 6 are sectional views on lines 45 5—5 and 6—6 respectively of Figure 2;

Figure 7 is a sectional view on line 7—7 of Figure 1.

The body 1 of the instrument may be of any desired or approved form and is shown equipped with the standard keys and valve pads controlled thereby, of which, however, for the present invention certain keys and valves only are of importance. In the pres-

ent specification reference is made to these valves and keys exclusively while the other equipment is not referred to.

Three keys, usually provided for operating the valves controlling production of the notes G, A and B respectively, are indicated at 2, 3 and 4 and are connected by arms 5, 6 and 7 respectively with the pertaining spindles to close the valves upon fingering of the keys as in other saxophones. The three fingers of the left hand of the player depress these keys while another finger opens at the same time the C valve 8, as for instance by manipulation of key 9, if the note G just above the staff is to be produced.

In order to produce notes of a higher register, these keys, or some of them, have to be operated together with additional keys, controlling valve pads at a portion higher up on the instrument. Additional valve pads for the production of these tones of higher register are indicated at 10 for the tone C-flat, at 11 for D-flat, at 12 for E, and at 13 for F. By reference to Figure 2 it will be seen that the valve pads 10, 11, 12 and 13 are associated with arms 14, 15, 16 and 17 respectively, which are fixed on spindles or shafts extending to different keys near the lower part of the instrument. But these keys cannot readily be manipulated if at the same time other keys are to be fingered.

According to the present invention the necessity of operating under these conditions the individual keys for the valves 10 to 13 inclusive is dispensed with and the opening movement of these valves conjointly is controlled by a master key. The master key 18 is located near the more accessible part of the instrument and is fixedly connected with a spindle 20 supported in the bearing 19 near the lower part of the instrument and in the bearing 21 near the upper part of the same.

A lateral arm 22 fixed to the spindle 20 extends to the valve 11, which is the D-flat valve, and rests thereon to keep this valve closed, the valve having a tendency to open when the arm 22 is raised. It will be seen, therefore, that by operation of the master key 18 a rocking movement is imparted to the spindle 20 and this rocking movement is utilized by means of the lateral arm 22 to permit the valve 11 for the tone D-flat to open. This valve 11 is equipped with an arm 23 extending

to the valve 12 for the tone E of the higher register, and similarly the valve 12 has an arm 24 extending to the valve 13, the arms 23 and 24 being secured respectively to the 5 pertaining valves to cause closure of the valve on which the arm loosely rests, when the next preceding lower valve is closed. These valves for D-flat, E and F, therefore, are constructed to open automatically upon actuation of the 10 master key 18, and remain normally closed unless actuated by their pertaining keys, or by the master key.

It is apparent from the above that upon manipulation of the master key 18 the valves 15 controlling tones of a higher register are opened simultaneously. In order to produce certain tones, however, it is not only necessary to open these valves 11, 12, 13 in conjunction, but it is also essential that some of the valves 20 used in the production of tones of lower register should be manipulated.

This manipulation of the valves for the tones of lower register, however, is the standard manipulation, as for instance the depression of the keys 2, 3 and 4 effecting the closure of the valves for the tones G, A and B respectively. Now owing to the closure of the valves for these tones of the lower register the tones would cease to be resonant, and it is 30 therefore an aim of the invention to combine with the operation of the master key also the operation of some additional valves, which may produce tones harmonically equivalent to those of the valves 2, 3, 4 and taking the 35 place of the valves for the tones G, A and B.

For this purpose the instrument is equipped with an additional set of valves 25, 26, 27 as shown in Figure 3 and secured by arms 28, 29 and 30 respectively to a common spindle 31 40 supported in the bearings 32 and 33 on the body 1 of the saxophone. It is obvious, therefore, that upon the operation of the spindle 31 in its bearings these three additional valves 25, 26 and 27 will be operated and will compensate for the fact that the tones G, A, B under control of the keys 2, 3 and 4 have lost 45 their resonance. For the purpose of manipulating the spindle 31 an arm 37 is secured to the same and projects with its free end 50 underneath a pin 34, Figures 2 and 6, of a rocking lever 35 supported in a bearing 36 which is secured to the body 1 of the instrument. This lever 35 carries another pin 38 at the other end, and this pin 38 projects above 55 the arm 22 directly secured to the spindle 20 of the master key 18, whereby upon actuation 60 of the master key the arm 22, swinging in anti-clockwise direction, Figure 6, communicates a rocking movement to the lever 35 in the opposite direction, and thereby actuates the spindle 31 to which the three valves 25, 26 and 27 are secured. The arm 22 for this 65 purpose is provided with a small seat or indentation 39 in which the pin 38 rests.

The operation of the master key 18 there-

fore leads to simultaneous opening of the valves 11, 12 and 13 and to the opening of the valves 25, 26 and 27. The player of the instrument now can readily alter the combination of the key 2, 3 and 4, on which three fingers of the left hand rest, to vary the high register tones produced by the opening of the valves 11, 12 and 13. 70

In order to produce the tones of a higher octave it is also necessary to manipulate a 75 high octave valve which is usually located close to the mouthpiece of the instrument, and the manipulation of this valve (not shown in the drawing) is here, as in many other instruments, effected by means of a ring 40 spaced 80 from and surrounding the instrument near the neck thereof and connected with a lever 41 which has its pivots in the bearing 42. Near the bearing 21 of the spindle 20 for the master key an arm 43 projects substantially in forward direction to engage at its free end the tail portion of an angular lever 44 which is pivoted intermediate its ends through spindle 45 in bearings 46. The free end of the lever 44 engages the inner circumference of the ring 40, whereby upon manipulation of the master key 18 this ring is moved laterally of its axis and a rocking movement is imparted to the lever 41 which then will open the octave valve 85 (not shown) located close to the mouthpiece 90 of the instrument.

While the manipulation of any of the keys 2, 3 or 4 will permit of a variation of the high register tones, the production of which is due to the opening of the valves 11, 12 and 13, the 100 production of the tone F in the higher register requires that the C valve also should be opened, and as it would be very difficult for the player to manipulate at the same time the key which causes resonance of the C valve 8, 105 the master key 18 also actuates instrumentalities through which this tone is rendered resonant.

As the C valve 8 is to be opened conjointly with the master key a lateral projection 47 110 extends from the valve lever 48 beneath an arm 49 secured to the spindle 20. The lateral projection 47 terminates in a pin 50 offset from the arm and extends in direction of the lever 48, and the arm 49, projecting from the 115 spindle 20, overlies said pin 50 whereby upon depression of the master key 18 the valve 8 is manipulated in the same manner in which this valve would be manipulated if its pertaining individual key 9 should be depressed. 120

The operation of the instrument for the production of higher register tones will become apparent from the following:

The conjoint manipulation of the individually operable valves of the G, A and B tones 125 together produces the note G, just above the staff. The manipulation of these valves together with the valves for the tones D-flat, E and F of the higher register and conjointly with the operation of the C valve will pro- 130

duce the high D, provided the octave valve also is actuated. It is obvious, therefore, that a conversion of the high G just above the staff into a D of still higher octave is effected by the simultaneous depression of the master key and the keys 2, 3 and 4.

The A just above the staff is produced by the manipulation of the keys A and B without closure of the G valve. This tone A just above the staff may readily be converted into a still higher D-flat by depression of the keys 3 and 4 for the tones A and B, and at the same time manipulating the master key, whereby the valve pads 9, 10 and 11 are actuated.

The manipulation of the B key without simultaneous closure of the G and A valve will produce the still higher E, if at the same time the master key is operated and the valve pads 9, 10 and 11 are thereby actuated, hence the high B is converted into a very high E.

Finally, by depression of the master key and raising the first finger on the left hand off the B valve and higher register tone valves, the instrument will convert the high C-flat into the high F.

It is obvious from the above that the high tones can be produced as fast and as readily as the normal tones G, A and B since the task of rendering the non-resonant valves resonant and at the same time manipulating the octave key, is taken care of by the operation of the master key.

I claim:

1. In a saxophone, a valve controlling a higher register tone, an individually operable valve controlling a tone of a lower register, a unitary set of resonant valves adapted to render the lower tone resonant when said tone ceases to be resonant upon closure of the second named valve, and means for causing simultaneously the opening of the higher register tone valve and the resonant tone valves.

2. In a saxophone, a plurality of valves for tones of a higher register, said valves being interconnected to effect movement of all of the valves upon actuation of a certain valve of said plurality, a master key controlling said plurality of valves and connected with said certain valve only, a plurality of individually operable valves for tones of a lower register, said tones ceasing to be resonant upon closure of said valves, and means controlled by the master key for rendering the tones controlled by the second named valves resonant after the second named valves have been closed.

3. In a saxophone, the combination of a plurality of valves for higher register tones, means for individually operating said valves, one of said valves being normally closed and others of said valves being normally open, means under control of the master key for releasing the first named valve from its normally closed position, and means controlled by said valve for releasing the other of the

valves from their normally open position to shut position.

4. In a saxophone, the combination of a set of valves for higher register tones, one of the valves being normally closed and others of said valves being normally open, a master key, an arm projecting from said master key over said normally closed valve to permit release of said normally closed valve from closed position upon operation of said master key, and an arm projecting from said valve over another valve of the plurality and adapted to close said other valve when the first named valve is being closed.

5. In a saxophone, the combination of a plurality of valves for higher register tones, a master key, a spindle to which said master key is secured, an arm projecting from the spindle over one of said valves which is normally closed to release the same from closing position upon actuation of the master key, another set of valves, and means controlled by said arm for manipulating the other set of valves.

6. In a saxophone, the combination of a plurality of valves of a higher tone register, an actuating element for an octave valve, a master key, and separate means under control of the master key for permitting simultaneously actuation of said higher register tone valves and for operating the actuating element of said octave valve.

7. In a saxophone, the combination of a plurality of valves for higher register tones, means for individually operating said valves, a master key adapted to effect actuation of all of said valves to open position simultaneously, an octave valve actuating member, and means under control of the master key for manipulating said octave valve actuating member simultaneously with said first named means.

8. In a saxophone, the combination of D-flat, E and F valves, individual operating means for the same, a master key holding the D-flat, E, and F valves inactive while tones below high C-flat are being produced, another set of rigidly interconnected valves, and means acting on the D-flat valve only, and under control of the master key for rendering said valves active and for simultaneously opening the other set of valves.

9. In a saxophone, a C-valve, means for individually operating the same, individually operable G, A and B valves, said last named valves ceasing to be resonant upon their closure, a master key, and means under control of the master key for rendering said tones resonant and for operating simultaneously the C-valve.

10. In a saxophone, a plurality of individually operable valves for producing tones which cease to be resonant upon closure of the respective valve, a plurality of auxiliary valves, a spindle to which said auxiliary

valves rendering the non-resonant tones resonant are secured, an arm projecting from said spindle, a lever controlling the arm, a master key, a spindle on which said master key is mounted, and an arm on said last named spindle for controlling said lever.

11. In a saxophone, the combination of a plurality of high register tone valves, a master key, an element under control of the master key for normally maintaining said high register tone valves closed, a set of individually operable valves controlling tones which cease to be resonant upon the closure of said last named valves, a plurality of auxiliary valves adapted to reestablish the resonance of said tones when opened, and means under control of the element controlling the higher register tone valves for opening said auxiliary valves.
12. In a saxophone, a set of valves for higher register tones, a master key, and means under control of the master key connected with one valve of said set only for keeping

said valves normally closed and for closing said valves for higher register tones upon operation of said master key.

13. In a saxophone, the combination of a plurality of individually operable valves for tones of a lower register, a plurality of auxiliary valves for tones of the same register, said auxiliary valves being rigidly interconnected, and a common means for opening all of said auxiliary valves, said auxiliary valves being harmonically the equivalent of said individually operable valves.

14. In a saxophone, the combination of a plurality of individually operable valves, a plurality of individually operable valves for tones of a higher register and normally closed, and means acting on one of said valves only for releasing all of said last named valves simultaneously from closed position.

In witness whereof I have hereunto affixed my signature this 30 day of November, 1925.

AVERY J. HILTON.
